HAROLD W. HOLMES, OF DETROIT, MICHIGAN, ASSIGNOR, BY MESNE ASSIGNMENTS, TO
CINCINNATI GRINDERS INCORPORATED, OF CINCINNATI, OHIO, A CORPORATION OF
OHIO

CENTERLESS GRINDING MACHINE

Application filed October 21, 1935. Serial No. 33,907.

This invention relates to grinding machines and more particularly to centerless grinding machines wherein cylindrical work is caused to pass between a slowly rotated work regulating wheel and a rapidly rotated grinding wheel for grinding.

On account of the relatively small surface bearing against the work regulating wheel and the grinding wheel, considerable difficulty has been experienced heretofore in grinding thin cylindrical work, such as ball or roller bearing races, brake shoes, rings, discs, and the like. There has been a tendency for such work to twist during grinding as well as to fall over owing to its unstable condition when standing on edge, and it has been difficult to feed the work to a grinding position with its axis maintained in proper relation to the grinding wheel axis. In order to grind such cylindrical work satisfactorily the axis of the work must be maintained, during grinding, in a predetermined angular position with respect to the grinding wheel axis; otherwise a tapered or irregularly shaped surface is ground upon the work.

It is accordingly an object of the invention to provide an improved machine for grinding relatively thin work having a cylindrical surface.

Another object of the invention is the provision of means permitting the passage of a plurality of thin cylindrical work pieces, such as ball races, through the machine in such a manner that each work piece tends to support and keep adjacent work in such a position that a cut taken on the outside surface by the grinding wheel will be parallel to the work axis.

The common practice in centerless grinding has been to skew the regulating wheel relative to the grinding wheel and the work in order to feed the latter through the grinding zone. For certain types of work it may be inadvisable to depend on the regulating wheel for carrying on the feeding operation, and it may be desirable to provide a power feeding mechanism to supplement or to replace the feeding action of the regulating wheel.

It is therefore a further object of the in-

vention to provide a centerless grinding machine with a power driven feeding mechanism capable of moving a plurality of pieces of work axially through the grinding zone and of maintaining the work pieces in alignment and properly positioned for grinding.

It is another object of the invention to provide a centerless grinding machine in which the wheel axes may be maintained parallel and the work forced automatically through the grinding zone by an externally applied force, or in which such force may be employed to assist and supplement the feeding action of the regulating wheel which has its axis skewed relative to the axis of the work.

Further objects will be apparent to one skilled in the art.

In accordance with certain features of the invention, I provide mechanism operatively associated with the grinding wheel and the work regulating wheel of a centerless grinding machine for positively moving cylindrical work toward a grinding position between the wheels in a direction parallel to the axis of the work. This work may then be forced by such mechanism through the grinding zone while axially parallel with the regulating wheel, but I prefer to skew this wheel relative to the work so that the latter will be fed by the action of the wheel after it has come in contact therewith, and the pushing mechanism may in that case serve merely to supply the work to the wheels in proper position for grinding or, depending upon the relative forces employed, to assist the regulating wheel in moving the work through the grinding zone. My preferred form of pusher mechanism comprises a work guiding support and a pusher, operated by a weight or the like, to move the work along the support. For this purpose, I may provide guide rails extending to or between the wheels and mounted parallel to the axis of the grinding wheel. Means may be provided for causing a plurality of work pieces to travel in contact with each other along the rails toward the wheels to a grinding position. In accordance with my preferred practice, I move the work along the rails in a practically automatic manner, or in timed relation to the

work.

movement of the work between the wheels during grinding. Preferably, I provide a movable carriage which is held continuously under a pressure and engages the work to hold the pieces in contact with each other or to force them toward a grinding position.

The invention accordingly consists in the features of construction, combinations of elements, and arrangements of parts, all as will be exemplified in the structure to be herein-after described and the scope of the application of which will be indicated in the following claims.

The invention will be more clearly understood from the following description in conjunction with the accompanying drawings, in which is shown a preferred form of the various possible embodiments of this invention, and in which—

20 Fig. 1 is a front elevation of a centerless grinding machine embodying the invention;

Fig. 2 is a sectional view of a portion of the machine taken along the line 2—2 of Fig. 1;

25 Fig. 3 is a sectional view taken upon the line 3—3 of Fig. 1;

Fig. 4 is a side elevational view of the machine in partial section and with parts removed or broken away; and

30 Fig. 5 is a detail view of the outwardly movable fingers on the movable carriage.

In the drawings, I have illustrated one type of centerless grinding machine embodying the invention and comprising a frame 5 in which suitable bearings are mounted for carrying a grinding wheel spindle 6 upon one end of which a grinding wheel 7 is mounted. A driving pulley 8 is mounted upon the other end of the grinding wheel spindle 6 and is rotated by means of a belt 9 passing over a pulley 10 upon a shaft 11, driven from any appropriate source of power. A work regulating wheel 12 is mounted in any appropriate manner on a shaft 13 fitted in suitable bearings on the vertical arms of a V-shaped support 14 pivotally secured upon the top of the column 15. The water pan 16 surrounds the regulating wheel and is secured to the column 15 by means of bolts 17, passing through the flange 18 on the column. The 40 regulating wheel 12 normally is positioned with its axis skewed relative to the grinding wheel axis, but may be adjusted so that its axis is parallel to the axis of the grinding wheel by means of a bolt 19 passing through an arcuate slot 20 in the support 14 and into a threaded hole in the column. The column 15 may be held against turning in the pillar 21 by means of a key.

60 The work regulating wheel 12 is rotated relatively slowly through the instrumentality, for example, of bevel gears 23, shafts 24 and 25, which are connected by telescoping shaft 26 and universal connections 27, and intermeshing bevel gears 28 secured on the shaft 24 and the work regulating wheel shaft

13. The regulating wheel may be adjusted toward or away from the grinding wheel by means of a hand wheel 29 secured on one end of a shaft 30 and having an operating handle 31, the shaft 30 having a worm 32 on its other end engaging a worm wheel 33 on a screw shaft 34 passing through a threaded boss 35 on the pillar 21.

In accordance with certain features of the invention, suitable means are provided for feeding cylindrical work pieces to a grinding position between the grinding wheel and the work regulating wheel in an axial direction and in predetermined relation to the axis of the grinding wheel, in this instance 70 the axis of the work being parallel to the axis of the grinding wheel. This latter relation is preferred where the grinding wheel acts peripherally and is trued to substantially a true cylinder. This comprises as il-

lustrated blade-like members or work holding members located to support the work between the wheels and in operative contact therewith during the grinding operation, in combination with further guide rails along

80 which the work is pushed by a pusher mechanism toward the grinding zone. In the form shown, a plate 36 (Figs. 1 and 2) is secured upon each side of the pan 16 by means of bolts 38 within slots 39. The arms 40 are

85 pivotally mounted upon the raised portions 37 of the plate 36 to swing about a pivot bolt 41, and may be rigidly held in position by means of a bolt 42 in a slot 43. A pair

90 of guide rails 44 are secured to the upper ends 100 of the arms 40 by means of bolts 45, and pass between the grinding wheel and the work regulating wheel to guide thin cylindrical work to a grinding position. The slots 39

95 are shown as inclined at a slight angle to the vertical, so that as the plate 36 is raised or lowered the axis of the cylindrical work supported upon the rails 44 remains in substantially the same position laterally with respect to a line passing through the centers of 105

the wheels, the preferred position being a short distance from such a line.

The portions of the guide rails 44 passing directly between the wheels are bent downwardly or ground away slightly, as indicated 115 in Fig. 4, so as to permit the work to engage the work regulating wheel 12 without contacting with these guide rails 44 but to contact with the members 46 and 47 (see Fig. 4)

120 provided to hold the work correctly positioned during grinding. The work holding members 46 and 47 are mounted upon the forwardly extending arms 48 secured to an auxiliary sliding frame having the rack 49

and may be adjusted up and down by turning the wheel 50 which is appropriately connected to a pinion (not shown) for moving the rack. The arms 40 may be adjusted to move the rails 44 toward or away from each other by means of an adjusting screw 51 en-

125

130

gaging a stationary nut 52 and passing through self aligning nuts 53 pivotally mounted in slots 54 in the arms 40. A knurled knob 55 is provided on the end of screw 51.

A supporting member 56 in the form of an elongated bar is rigidly secured in a socket 57 on the positioning plate 36 and has a longitudinal slot 58 on the top and bottom (Figs. 2 and 1) for guiding the rollers 59 which are pivotally mounted upon a carriage 60 (Figs. 1 and 3). A plurality of arms 61 are adjustably mounted upon the carriage by means of bolts 62 and each carries a flexible or outwardly movable finger 63 (see Fig. 5) held in its innermost position by means of a spring 64. The end of each finger is adapted to engage the work 65 upon the rails. The fingers are so located that they will exert a pressure at proper points adjacent the edge of the work, and against the rear surface thereof, tending to keep the work standing straight. The carriage 60 is movable toward the wheels by the action of adjustable weights 66 (Fig. 1) suspended upon one end of a cord 67 secured on a pin 68 on the carriage and passing over a pulley 69. The carriage may be manually moved away from the wheels by means (Fig. 3) of a handle 70.

It will be understood that the weight 66 may be adjusted so as to exert a force against the work pieces which is more than sufficient than that required to hold the work pieces against work being ground. Thus, the weight 66 may be made heavy enough to actually push the work piece being ground through the grinding zone.

I have obtained very satisfactory results in grinding thin cylindrical objects, such as ball races, brake shoes, and the like, when the work regulating wheel 12 is skewed relative to the axis of the grinding wheel through an angle of about $1\frac{1}{2}$ degrees. This is accomplished by loosening the bolt 19 (Fig. 4) and moving the regulating wheel support 14 to the required angle. The guide rails 44 are secured upon the pan 16 so as to be parallel with the line of contact of the grinding wheel with the work and, where the grinding wheel is trued to a straight cylinder, they will also be parallel with the axis of the grinding wheel. The position of the regulating wheel 12 may be adjusted toward or away from the grinding wheel to accommodate various sizes of work by turning the hand wheel 29 by means of the handle 31 (Fig. 1) which actuates through an appropriate mechanism the screw 34 for raising or lowering the column 15. For different sizes of work the position of the guide rails 44 may be adjusted by turning the knurled knob 55 to move the adjusting screw 51. The position of the fingers 63 may be adjusted by loosening the bolts 62 and

sliding the arms 61 along the outer surface of the carriage 60.

In the grinding of thin cylindrical objects, such as ball races, a suitable number of work-pieces (indicated at 65 in Figs. 1, 2 and 3) are placed upon and between the rails 44 (see Figs. 2 and 3) and the latter should be adjusted to support the work at a point, preferably, about one third the diameter of the work away from the bottom thereof to steady the work and oppose its tendency to twist. The carriage 60 is moved to the right, as seen in Fig. 1, by the handle 70, thus raising the weights 66, and is thus positioned along the member 56 to bring the fingers 63 in contact with the back or rear end of the end-most work-piece (the right hand end piece of the work-pieces 65, as seen in Fig. 1) and the carriage 60 released, whence weights 66 urge the latter to the left to keep the various pieces in contact with each other so that each supports its next adjacent piece in position axially parallel to the axis of the grinding wheel, or the work being ground, and at the same time cause the work pieces 65 to be pushed along the rails 44 at the same rate as the work moves between the wheels during grinding. The preferred arrangement and action of the several parts of the apparatus are such that the regulating wheel 12 pre-

determines the rate of axial feeding movement of the work-pieces 65 as the latter pass through the grinding throat, and that the carriage 60, in moving toward the left, as seen in Fig. 1, under the urge of the weights 66, causes such work-pieces 65 as are to the right of the grinding throat to steadily follow up such work-pieces as are being fed through the grinding throat by the regulating wheel 12, at the same time preventing the work-pieces 65 that are outside of the grinding throat from tilting, and thus insuring that they are presented to the grinding throat precisely and accurately in alinement with the elements of the grinding throat. While the plurality of thin work pieces are being pushed toward their grinding position between the wheels, additional work pieces may be loaded upon the rails in back of the fingers 63 and between the arms 61 (Fig. 1). These may be pushed against the work previously placed upon the rails by drawing the carriage in a direction away from the wheels by means of the handle 70 so that the fingers engage the last work piece. In so doing, the flexible fingers move outward to pass over the work to the last work piece and then spring in to engage the same so that the new work pieces are pushed forward due to the action of the weights 66 tending to move the carriage 60 toward the wheels.

When the work piece has progressed along the rails 44 until it reaches the bent or ground away portions of the rails, these portions permit the work to drop downwardly a short

distance into engagement with the regulating wheel, which, as may be seen in Figure 1, has a greater width of operative surface than the grinding wheel, and projects outwardly beyond the grinding wheel toward the advancing work pieces. As soon as the work pieces leave the rails 44 and engage the regulating wheel surface they start to rotate, and they are thus in rotation when they enter the grip of the two wheels; thereafter, the work pieces, continually rotated by the regulating wheel and being ground by the grinding wheel, move through the grinding zone held in position by the members 46 and 47. The work does not contact with the rails while being ground but as it continues through the machine and leaves the regulating wheel it may be and, preferably, is again supported by the rails, which guide the same to an appropriate point of discharge, such for example as a discharge trough 71.

The machine illustrated is particularly adapted for grinding a succession of discs, such as ball races, which are passed through the machine in a practically automatic manner and in such a way that each disc tends to support and keep its neighbor disc upright so that the cut taken on the outside surface will be at right angles to the sides, or parallel to the work axis. The pressure of the carriage, or the flexible fingers carried thereby, in forcing the discs into a position for grinding, preferably, is just sufficient to keep a constant in-pressure on the discs so that there is no gap between any two discs at the time the control or work regulating wheel starts to give motion to them and carry them through the machine. I have obtained satisfactory results with the parts of the machine so constructed and arranged that there is no actual pushing of such thin work during grinding and the carriage does not tend to skid the work across the regulating wheel.

It is to be understood that this machine will handle relatively long or thick pieces of work and that it is not limited in use to the grinding of discs. But it will be seen that many thoroughly practical advantages are achieved when the apparatus operates upon work pieces whose axial length is relatively small compared with the diameter thereof. Moreover, in accordance with the above disclosure, the weight 66 may be increased to such an extent that it will help the skewed regulating wheel force the work past the grinding wheel. If desired, the regulating wheel may be located with its axis parallel with that of the work, and in that case the regulating wheel will not feed the work axially but then the weight 66 may be so adjusted that it will serve alone to push the work through the grinding zone.

It will thus be seen that there has been provided in this invention an apparatus in which the several objects hereinabove noted,

as well as many thoroughly practical advantages, are successfully achieved, and it will be seen also that the apparatus is well adapted to meet the varying conditions of hard, practical use.

As many possible embodiments may be made of the above invention and as many changes might be made in the embodiment above set forth, it is to be understood that all matter hereinbefore set forth or shown in the accompanying drawings is to be interpreted as illustrative and not in a limiting sense.

Having thus described my invention, what I claim as new and desire to secure by Letters Patent is:

1. In a grinding machine, in combination, a grinding wheel adapted to be rotated at a relatively high speed, a regulating wheel adapted to be rotated at a relatively low speed, means for holding between said wheels and in operative relation thereto a succession of thin cylindrical work pieces positioned face to face, the path of travel of the face of said regulating wheel being inclined with respect to the axis of the work thereby to exert an axial feeding component upon the work, and means adapted to bear yieldingly in an axial direction against said work pieces to hold their adjacent end faces in contact whereby said work pieces tend to support each other against twisting.

2. In a grinding machine, in combination, a grinding wheel adapted to be rotated at a relatively high speed, a regulating wheel adapted to be rotated at a relatively low speed, means for holding work between said wheels and in operative relation thereto, the path of travel of the operative face of the regulating wheel being inclined with respect to the axis of the work to exert an axial feeding component upon the work, and a work presenting mechanism including means for supporting a plurality of pieces of work, and means adapted to move said work pieces along said supporting means in contact with each other and axially parallel with the work piece being ground and at a rate substantially equivalent to the rate of axial feeding caused by said regulating wheel and to support the latter and hold its axis against twisting during the grinding operation.

3. In a grinding machine, in combination, a grinding wheel adapted to be rotated at a relatively high speed, a regulating wheel adapted to be rotated at a relatively low speed, means for holding work between said wheels and in operative relation thereto, supporting means mounted substantially parallel to the axis of the work being ground for carrying pieces of work toward the wheels, and reciprocable means for feeding contacting work pieces along said supporting means to a grinding position, said reciprocable means having a work-feeding stroke sufficient

in length to move a plurality of said work-pieces through the grinding zone.

4. In a grinding machine, in combination, a grinding wheel adapted to be rotated at a relatively high speed, a regulating wheel adapted to be rotated at a relatively low speed, means for holding work between said wheels and in operative relation thereto, the path of travel of the operative face of the regulating wheel being inclined with respect to the axis of the work to exert an axial feeding component upon the work, means for varying the inclination between the axis of the work and the path of travel of the operative face of the regulating wheel to vary the rate of axial feeding movement of the work, and means for feeding a succession of work pieces toward a grinding position at substantially the same rate as the work being ground is moved axially by the regulating wheel and operating thus even though the rate of feeding movement by the regulating wheel is varied and for holding the axis of the work being ground against twisting.

25 5. In a grinding machine, in combination, a grinding wheel adapted to be rotated at a relatively high speed, a regulating wheel adapted to be rotated at a relatively low speed, means for holding work between said wheels and in operative relation thereto, means for supporting a succession of work pieces with their axes extending in substantial alignment with the axis of a work-piece being operated upon by said wheels and for entrance axially into a grinding position between said wheels, a movable carriage operatively associated with said supporting means, and means for applying a yieldable force to said carriage for moving said carriage to hold the work pieces in contact while yieldingly moving the same along said supporting means to a position for grinding.

40 6. In a grinding machine, in combination, a grinding wheel adapted to be rotated at a relatively high speed, a regulating wheel adapted to be rotated at a relatively low speed, means for holding work between said wheels and in operative relation thereto, means for supporting a succession of work pieces with their axes extending in substantial alignment with the axis of a work-piece being operated upon by said wheels and for entrance axially into a grinding position between said wheels, a carriage for moving the work pieces along said supporting means, and means for applying an adjustable force to move said carriage and to hold the work pieces in contact with each other.

45 7. In a grinding machine, in combination, a grinding wheel adapted to be rotated at a relatively high speed, a regulating wheel adapted to be rotated at a relatively low speed, means for holding work between said wheels and in operative relation thereto, means for supporting a succession of work

pieces for entrance axially into a grinding position between said wheels, a carriage operatively associated with said supporting means and adapted to move toward and away from the wheels and having outwardly movable projecting fingers, spring means adapted to hold said fingers inwardly to engage the work, and means for moving said carriage to hold the work pieces in contact on said supporting means while moving the same toward a grinding position.

8. In a grinding machine, in combination, a grinding wheel adapted to be rotated at a relatively high speed, a regulating wheel adapted to be rotated at a relatively low speed, means for holding work between said wheels and in operative relation thereto, means for supporting a succession of work pieces for entrance axially into a grinding position between said wheels, a carriage operatively associated with said supporting means and adapted to move toward and away from said wheels and having projecting fingers adapted to engage the work pieces on said supporting means, means for adjusting said fingers toward and away from each other for engaging work pieces of various sizes, and means for moving said carriage to hold the work pieces in contact while moving the same along said supporting means toward a grinding position.

9. In a grinding machine, in combination, a grinding wheel adapted to be rotated at a relatively high speed, a regulating wheel positioned below said grinding wheel and adapted to be rotated at a relatively low speed, means for holding work between said wheels and in operative relation thereto, and means for feeding a succession of thin cylindrical work pieces toward a grinding position, said means holding an end-most work-piece with its axis substantially aligned with a work-piece being ground and moving with said end-most work-piece for maintaining the axis of the remaining work-piece against tilting.

10. In a grinding machine, in combination, a peripherally operative grinding wheel adapted to be rotated at a relatively high speed, a regulating wheel positioned below said grinding wheel and adapted to be rotated at a relatively low speed, means for holding work between said wheels and in operative relation thereto, means mounted substantially parallel to the axis of the grinding wheel and arranged to carry cylindrical work pieces onto the regulating wheel to be rotated thereby during grinding, and means for pushing the work pieces into contact and along said last means toward a grinding position.

11. In a grinding machine, in combination, a grinding wheel, means for holding work with its periphery in operative relation thereto, means for supporting a succession of thin

cylindrical work pieces in position for movement axially into operative relation to said wheel, and power-actuated means adapted to feed said work pieces axially along said supporting means toward grinding position and movable with said work-pieces to support said thin pieces against tilting out of proper axial relation to said grinding wheel as they move into operative engagement with said grinding wheel and said work-holding means.

12. In a grinding machine, in combination, a grinding wheel, means for holding work with its periphery in operative relation thereto and adapted to take up the thrust of the grinding wheel on the work, means for supporting a succession of thin cylindrical work pieces in position for movement axially into operative relation to said wheel, a carriage movable along said supporting means, means upon said carriage adapted to bear against the end face of the rearmost work piece, and means for moving said carriage to force said work pieces along said supporting means and into operative relation to said wheel and said work-holding means.

13. In a grinding machine, in combination, a grinding wheel adapted to be rotated at a relatively high speed, means coacting therewith for supporting cylindrical work pieces in operative engagement with said grinding wheel and for rotating said work pieces, said means including a rotary member adapted to be driven at a relatively low speed and having a portion extended beyond the operative face of said grinding wheel, means for supporting cylindrical work in position for movement axially into operative engagement with said grinding wheel, and means for feeding said work along said supporting means and into engagement with said extended portion of said rotary member to be rotated thereby preliminarily to its entry into operative relation to said grinding wheel.

14. In a grinding machine, in combination, a grinding wheel adapted to be rotated at a relatively high speed, means for supporting a succession of thin work pieces for entrance axially into operative engagement with said grinding wheel, means adapted to move said work pieces along said supporting means and to hold them against tilting out of proper axial position for grinding, and means adapted to receive said work pieces from said supporting means and to support and rotate said work pieces in operative relation to said grinding wheel, said last means including a rotary member adapted to be rotated at a relatively low speed and having a portion extended beyond the face of the grinding wheel in a direction toward the advancing work pieces whereby said work pieces are rotated preliminarily to their entrance into operative relation with said grinding wheel.

15. In a grinding machine, in combination, a grinding wheel adapted to be rotated at a relatively high speed, a regulating wheel adapted to be rotated at a relatively low speed and positioned beneath said grinding wheel, and means adapted to support a succession of cylindrical work pieces for entrance axially into the grinding zone between said two wheels and at an elevation slightly higher than the portion of said regulating wheel which engages the work, said regulating wheel being extended beyond the face of the grinding wheel and the extended portion thereof being adapted to receive the work pieces dropped thereon from said supporting means.

16. In a grinding machine, in combination, a grinding wheel adapted to be rotated at a relatively high speed, a regulating wheel adapted to be rotated at a relatively low speed and positioned beneath said grinding wheel, and means adapted to support a succession of cylindrical work pieces for entrance axially into the grinding zone between said two wheels and at an elevation slightly higher than the portion of said regulating wheel which engages the work, said regulating wheel being extended beyond the face of the grinding wheel and the extended portion thereof being adapted to receive the work pieces dropped thereon from said supporting means, and means adapted to hold the work pieces in position for proper engagement by the grinding wheel and the regulating wheel as they pass through the grinding zone.

17. In a grinding machine, in combination, a grinding wheel adapted to be rotated at a relatively high speed, a regulating wheel adapted to be rotated at a relatively low speed and positioned beneath said grinding wheel, said regulating wheel having a portion extended beyond the face of the grinding wheel, means adapted to deliver cylindrical work pieces axially to said extended regulating wheel portion and at an elevation slightly higher than the portion of said regulating wheel which engages the work, and means adapted thereafter to hold said work in position for proper engagement by the grinding wheel and the regulating wheel as it passes through the grinding zone.

18. In a grinding machine, in combination, a grinding wheel adapted to be rotated at a relatively high speed, a regulating wheel adapted to be rotated at a relatively low speed, means for holding work between said wheels and in operative relation thereto, and means for feeding a succession of work pieces for entrance axially into a grinding position between said wheels, said last means including an elongated support along which the work pieces are adapted to slide axially and a carriage slidable in a direction lengthwise of said support and adapted to push the work

pieces into operative position between said wheels, the carriage being arranged to permit placing additional work pieces on said support rearwardly of the carriage as the carriage advances.

19. In a grinding machine, in combination, a grinding wheel adapted to be rotated at a relatively high speed, a regulating wheel adapted to be rotated at a relatively low speed, means for holding work between said wheels and in operative relation thereto, and means for feeding a succession of work pieces for entrance axially into a grinding position between said wheels, said last means including an elongated support along which the work pieces are adapted to slide axially and a carriage slidable in a direction lengthwise of said support and adapted to push the work pieces into operative position between said wheels, the carriage being arranged to permit placing additional work pieces on said support rearwardly of the carriage as the carriage advances, fingers on said carriage yieldingly pressed inwardly toward the axes of the work pieces and adapted to engage the rear end of the work pieces to urge them along said support, said fingers being arranged to swing outwardly and clear the work pieces rearwardly of the carriage as the carriage is moved rearwardly.

20. In a grinding machine, in combination, a grinding wheel adapted to be rotated at a relatively high speed, a regulating wheel adapted to be rotated at a relatively low speed, means for holding work between said wheels and in operative relation thereto, means for supporting a succession of work pieces for entrance axially into a grinding position between said wheels comprising two rails spaced apart and adapted to engage the sides of the work pieces below the axes thereof, means for adjusting the position of said rails to accommodate work pieces of different sizes, and means for forcing the work pieces along said rails to feed them into grinding position.

21. In a grinding machine, in combination, a grinding wheel adapted to be rotated at a relatively high speed, a regulating wheel adapted to be rotated at a relatively low speed, means for holding work between said wheels and in operative relation thereto, means for supporting a succession of work pieces for entrance axially into a grinding position between said wheels, a carriage operatively associated with said supporting means and movable lengthwise thereof and adapted to hold the work pieces in contact with each other and move the same along the supporting means to a position for grinding, a weight for moving said carriage in a direction to feed said work pieces toward grinding position, and a handle for manually retracting said carriage.

22. In a grinding machine, in combination,

a grinding wheel adapted to be rotated at a relatively high speed, a regulating wheel adapted to be rotated at a relatively low speed, means for holding work between said wheels and in operative relation thereto, means for supporting a succession of work pieces for entrance axially into a grinding position between said wheels, a support positioned beneath said work supporting means, and a carriage on said last support and movable thereon in a direction lengthwise of said work supporting means, said carriage having an upwardly projecting part adapted to engage the work pieces and move them along the work supporting means when the carriage is moved.

23. In a grinding machine, in combination, means forming a grinding throat for simultaneous rotating and grinding action upon work-pieces of round section and including a regulating wheel rotatable at relatively low speed and adapted to control the rotation of the work and a grinding wheel rotatable at grinding speed for performing the grinding operation upon the work; means for guiding work-pieces into said grinding throat; means movable toward and away from said grinding throat and adapted, upon movement toward said grinding throat, to move a work-piece positioned in advance thereof along said guiding means and into operative relation to the grinding throat, said movable means exposing a portion of said guiding means to the rear thereof for the reception of an additional work-piece; and means causing said movable means, upon movement in a direction away from said grinding throat, to by-pass said additional work-piece.

24. In a grinding machine, in combination, means forming a grinding throat for simultaneous rotating and grinding action upon work-pieces of round section and including a regulating wheel rotatable at relatively low speed and adapted to control the rotation of the work and a grinding wheel rotatable at grinding speed for performing the grinding operation upon the work; means for guiding work-pieces into said grinding throat and adapted to guide a succession of work-pieces; and means movable along said guiding means and in a direction toward and away from said grinding throat and adapted, upon movement toward the grinding throat, to move a succession of work-pieces positioned in advance thereof along said grinding means and into operative relation to the grinding throat, the portion of said guiding means along which said movable means has passed being thereby made available for the reception of another succession of work-pieces, said movable means being constructed to by-pass said last-mentioned succession of work-pieces when it is moved in a direction away from said grinding throat, whereby

said second-mentioned succession of work-pieces becomes positioned in advance of said movable means.

25. In a grinding machine, in combination, means forming a grinding throat for simultaneous rotating and grinding action upon work-pieces of round section and including a regulating wheel rotatable at relatively low speed and adapted to control the rotation of the work and a grinding wheel rotatable at grinding speed for performing the grinding operation upon the work; means for guiding work-pieces into said grinding throat; means movable toward and away from said grinding throat to move a work-piece positioned in advance thereof along said guiding means and into operative relation to the grinding throat, said movable means exposing a portion of said guiding means to the rear thereof for the reception of an additional work-piece; and means for yieldingly supporting the work-engaging portions of said movable means and adapted to permit said portions to clear said additional work-piece as said movable means is moved away from said grinding throat.

26. In a grinding machine, in combination, means forming a grinding throat for simultaneous rotating and grinding action upon work-pieces of round section and including a regulating wheel rotatable at relatively low speed and adapted to control the rotation of the work and a grinding wheel rotatable at grinding speed for performing the grinding operation upon the work; means extending away from said grinding throat and substantially in the direction of the axis of the work-piece operated upon for retaining a succession of relatively thin cylindrical work-pieces and guiding them in an axial direction into said grinding throat; and movable means engaging an end work-piece of said succession for moving said succession toward said grinding throat as the grinding throat performs its operation.

27. In a grinding machine, in combination, means forming a grinding throat for simultaneous rotating and grinding action upon work-pieces of round section and including a regulating wheel rotatable at relatively low speed and adapted to control the rotation of the work and a grinding wheel rotatable at grinding speed for performing the grinding operation upon the work; means extending away from said grinding throat and substantially in the direction of the axis of the work-piece operated upon for retaining a succession of relatively thin cylindrical work-pieces and guiding them in an axial direction into said grinding throat; a device engaging a work-piece in said succession remote from said grinding throat and movable in a direction toward the latter; and means causing movement of said device to effect movement

of said succession of work-pieces successively into said grinding throat.

Signed at Detroit, Michigan, this 12th day of October, 1925.

HAROLD W. HOLMES.
